SPINDLE-BACK CHAIR

Leonard Eisen, 14 Lomas Lane,
Montvale, N.J. 07645

Filed July 23, 1974, Ser. No. 491,123

Term of patent 7 years

Int. Cl. D6—01

U.S. Cl. D6—74

FIG. 2

FIG. 1

FIG. 1 is a front perspective view of a spindle-back chair showing my design; and

FIG. 2 is a right side view thereof.

The back of the spindle-back chair is plain and unornamented.

I claim:

The ornamental design for a spindle-back chair, as shown and described.
